UNITED STATES PATENT OFFICE.

FREDERICK M. TURCK, OF NEW YORK, N. Y.

MULTICOLOR-PRINTING PRESS.

1,146,039.

Specification of Letters Patent. Patented July 13, 1915.

Application filed May 22, 1913. Serial No. 769,186.

To all whom it may concern:

Be it known that I, FREDERICK M. TURCK, a citizen of the United States, and resident of New York, in the county of New York and State of New York, have invented certain new and useful Improvements in Multicolor-Printing Presses, of which the following is a specification.

The invention relates to improvements in multicolor printing presses in which rotating couples are employed to print two or more colors in superimposed relation upon sheets of material; and the objects of the invention are to provide a compact and readily accessible construction in which the sheets may be completely printed in one operation, to insure a more perfect register of the printed matter, and also to afford a uniform impression from the several printing plates. The invention also includes certain details of construction hereinafter set forth.

In describing the invention in detail reference is had to the accompanying drawings, forming a part of this specification, and wherein like characters of reference are used to designate corresponding parts throughout the several views, and in which:

Figure 1 is a ground plan of the press embodying the present invention, shown with certain well-known parts removed to more clearly illustrate the novel features thereof; Fig. 2, a sectional side elevation of the same, taken on the broken line $y-y$; Fig. 1, and including the feeding, delivering and inking mechanism; and Fig. 3 is a sectional side elevation of a single printing couple and sheet-carrier of a two-color press, shown as a modified form of construction.

Referring to Figs. 1 and 2, numeral 1 designates the base-plate of the press, upon which are mounted the fixed front and rear side frames 2 and 3 respectively. In these frames suitable bearings are provided in which are journaled for rotation the two sets of printing couples, composed of the form or plate cylinders 4 and 5 and the impression-cylinders 6 and 7. Each of the form-cylinders is divided circumferentially into three equal sections, two thereof being provided with printing plates, while the third is left blank or idle, the plates for cylinder 4 being indicated by the letters R and B and those for cylinder 5 by letters Y and BB, the several letters likewise re-

spectively indicating the commonly employed colors red, blue, yellow and black, arbitrarily arranged herein. The several plates are detachably secured in the usual manner upon the form-cylinders, and are adapted to engage for printing action the corresponding impression surfaces of the cylinders 6 and 7, indicated by r , y , b and bb , these surfaces being conventionally arranged with detachable draw and filling sheets to afford means of applying the necessary packing or "make-ready" for securing uniform impressions. As thus arranged, it will be obvious that each plate in its repeated revolutions will engage the same section of the impression surface and thereby preserve a corresponding uniformity in the impressions.

For imparting motion to the printing couples, a shaft 8 is mounted in bearings formed in the rear frame 3 and in the floor-stand 9, the shaft being provided with a power-pulley 10 and a driving pinion 11, the latter engaging the loosely-mounted intermediate gears 12, shown in broken lines in Fig. 2. The intermediates 12 engage gears 13, fixed upon the shafts of the impression-cylinders 6 and 7, and the latter gears in turn engage corresponding gears 14, fixed upon the shafts of the form-cylinders 4 and 5, the several gears being proportioned to rotate the several cylinders of the printing couples at a common rate of speed.

For advancing the work to be printed, a sheet-carrier is provided, composed of the oppositely-disposed annular side heads 15, connected together by the cross-braces 16, and arranged for rotation upon the bearing surfaces or runways 17, fixed upon the interior surfaces of the opposite side frames 2 and 3. Bearing-rollers 18 are preferably provided for the carrier-heads, and journaled therein for rolling contact upon the runways. For imparting rotation to the sheet-carrier, the heads thereof at their periphery are provided with gear-teeth 19, which are engaged by the gears 20, fixed to the shaft of the form-cylinder 4.

To the outer edges of the cross-braces 16 are fixed a series of thin annular bars arranged to divide the sheet-carrier circumferentially into seven equal sections, the bars and corresponding sections both being indicated by the numerals 21 to 27 inclusive. Each section adjacent the cross-brace thereof is provided with a set of grippers 28, ar-

ranged upon a rock-shaft in the usual manner, in yielding engagement with the upper edge of said cross-brace, to clamp therebetween the leading edge of a sheet to be printed, as fed from the feed-table 29. The annular bar sections of the carrier serve as interior supports for the sheets, and their circumferential lengths correspond severally with those of the sections of the form-cylinders, as measured upon the impression surfaces of the latter, and with which they are driven at a corresponding rate of speed, the circular path of the former being tangent to the line of printing contact of the two printing couples. To afford the necessary clearance for the path of the cross-bars and grippers of the carrier, longitudinally-extending recesses or grooves 30 are formed in the impression-cylinders 6 and 7, on opposite sides of the impression surfaces, which recesses also serve to contain the necessary fixtures for adjusting and retaining the cylinder cover sheets, these latter sheets being also spaced apart longitudinally of the cylinder for clearing the annular carrier-bars, the lateral spacing of which bars corresponds with that of the side and intermediate margins of the printed sheets.

As shown in Fig. 2, the sheets, as indicated in broken lines upon the carrier-sections and with respect to their printed conditions, are positioned in accordance with the general operation of the press, which positions, relative to the printing couples and to the feed and delivery devices, occur at each consecutive revolution of the couples. As indicated, the carrier-sections 24 and 27 contain no sheets, having immediately passed adjacent the blank sections on the form-cylinders in the latter's previous revolution; section 21 of the carrier holds a new sheet; section 22, a sheet having imprints of red and yellow colors; section 23, a sheet completely printed and ready for delivery; section 25, a sheet with a red imprint thereon; and section 26, one with red, yellow and blue imprints. During the following revolution of the printing couples each carrier-section will advance three divisions and the sheets on sections 21 and 23 will pass between the printing couples 4 and 6 and respectively receive the imprints R and B; likewise sheets on 25 and 26 will receive Y and BB imprints from the printing couple 5 and 7; the section 23 will deliver its sheet upon the delivery-tapes 31 and pass in blank relation with the blank section on form-cylinder 4; and the blank section 24 will receive a new sheet from the feed-table 29. It will be obvious that the several sections of the carrier as thus advanced the three divisions will, at the beginning and at the end of such movement, be similarly positioned with respect to the printed condition and feed and delivery of the sheets. In like manner each

succeeding revolution of the printing couples presents a corresponding condition, necessitating the feed of a new sheet and the delivery of a printed one. For completing a cycle of the carrier-section 21, it will be found that seven revolutions of the printing couples will be required as follows: in the first revolution the new sheet thereon will have received in its movement of three divisions a red impression, in the second revolution a red and yellow, in the third a red, yellow and blue, in the fourth a red, yellow, blue and black, in the fifth the sheet will have been delivered, in the sixth the section will have remained blank, and in the seventh a new sheet will have been fed thereto, all as severally indicated by the reference characters in the consecutive positions.

To provide for the delivery of a sheet at each revolution of a printing couple, the rock-shafts of the several sets of grippers 28 are each provided at one end with the usual grooved tumbler-head 32, operating in connection with a spring-rod movable with the carrier to normally retain the grippers either in an open or a closed position, the opening movement thereof being effected during the rotation of the carrier by the engagement of the slotted portion of the tumbler-head with the relatively fixed pin 33, disposed in off-set relation with the pivotal center of said head, all arranged in accordance with common practice and with respect to the delivery-tapes 31, which latter is likewise arranged in well-known manner with movable guide-bars 34, suitably timed for engagement with the lower portion of the leading edge of the advancing sheet for directing the latter upon the tapes. As the successive delivery of the sheets occurs only at each revolution of the printing couples or third divisional passage of the carrier-sections, the grippers on the intermediate sections will remain closed; and to provide for this condition the pin 33 is fixed in projecting relation upon an arm 35 of a lever pivotally mounted upon the rear side frame 3, the opposite arm of the lever being pivotally connected to a rod 36, engaged by a cam 37, fixed upon the supporting shaft of the form-cylinder 4, the cam being proportioned and positioned with regard to each revolution thereof to effect a movement of the pin into two relatively fixed positions, in one position thereof, as shown, the pin is aligned with the slotted tumbler-heads to effect the opening movement of the grippers, and in the opposite position the path of the heads is free of the pin, allowing the grippers of the intermediate sections to remain closed for further advancing their respective sheets. It will thus be obvious that upon the delivery of a sheet the grippers will remain open until again operated for the engagement of a new sheet supplied

from the feed-table. As the intervals of time occurring between the feed of successive sheets correspond with that of the successive deliveries, corresponding means are 5 employed for actuating the grippers to receive a new sheet, the same being preferably arranged upon the opposite ends of the gripper-rods and front side of the machine, the tumbler-heads thereof being indicated 10 by 38 and the cam by 39.

For affording additional support of the sheets with respect to the annular carrier sections at their upper portion of movement, a series of brushes 40 are mounted within 15 said carrier in relatively fixed relation upon a series of circumferentially-extending bars 41, secured to brackets 42, fixed to the side frame of the press. The bristles of the brush are sufficiently long and resilient to 20 engage the inner surfaces of the sheets in their path of movement and prevent an excessive sagging thereof between the annular carrier-bars, and also by their resilience are adapted to yield and retract under the contacting movement of the cross-braces 16 and 25 the grippers 28. Exteriorly of the carrier-sections, the free portion of the sheets in its path is controlled by the fixed guides 43, conveniently supported in any approved 30 manner; and also for urging the sheets in contact with the impression surfaces adjacent the line of printing contact to avoid premature engagement of the forms and consequent smearing of the sheets, air-supply pipes 44 are provided, having perforations arranged to suitably direct the air, obtained from any conveniently connected 35 source of supply.

The forms are provided severally with 40 independent and similar set of inking devices arranged to distribute ink of suitable color; as, from the fountain 45 to the form-rollers 46 by means of a series of intermediate rolls arranged and operated in the usual 45 manner. As herein shown, the form BB in its rotation is adapted to be yieldingly engaged by the form-rollers 46, the journal-boxes of which are provided with suitable 50 springs 47 and mounted for the movement necessary for the disengagement of their rollers from the form, which movement is effected by the engagement of a projecting bearing surface formed on each of the cams 55 48 with the guiding wheels 49, the former being fixed upon the shaft of the form-cylinder 5 and the latter loosely mounted upon the shafts of the form-rollers 46. It will be evident that by providing for the cams suitable projecting bearing surfaces for the 60 guiding wheels, the distribution of the ink may be limited to its proper printing form. In like manner the several sets of inking devices are arranged with cam-controlled form-rollers for the application of the ink 65 upon the forms.

As herein shown, the double set of inking devices for each of the form-cylinders are adapted to be mounted upon movable standards arranged independently of the main frames, from which they may be conveniently separated temporarily for adjusting both the printing forms and the inking rollers. These standards are indicated by the numeral 50 and are preferably provided with bearing rollers 51 arranged to run upon 70 tracks formed on the upper face of the base-plate 1, to which the standards are detachably secured in operative position.

To provide for initially inking the forms preparatory for the printing operation, the 80 form-cylinders thereof are disengaged from their respective impression-cylinders, the latter of which are mounted in the usual manner in slidable journal-boxes operatively connected for movement in opposite directions by the toggle-arms indicated by the 85 numeral 52, the latter being actuated by the rod 53 in any approved manner.

In the construction of the form-cylinders 4 and 5, it will be obvious that the relatively 90 increased diameter thereof, due to the double form sections and the necessary addition of the blank surface thereon, will have certain advantages, not only with respect to the construction of the connected printing 95 plates in requiring a less degree of stretch and distortion in the bending process thereof, but also as regards the inking of the plates, in affording a considerably greater amount of time for a more thorough distribution of the ink over the several rollers between successive applications to the forms. The increased diameter of these form-cylinders also permits the use of form-rollers of 100 relatively greater diameter, thus allowing 105 of increased spacing of certain of the parts to render the same accessible to the operator.

It will be evident in the operation of the printing press as herein described and shown in Figs. 1 and 2, that a plurality of 110 sheets at one handling may be printed with four superimposed impressions; also, that the same press may likewise make three impressions by the disconnection of a form from one of the form-cylinders; or, by operating upon one form-cylinder only may 115 make two superimposed impressions upon the sheets, or even a single impression thereon.

In the modification shown in Fig. 3, the 120 numerals 54 and 55 designate respectively the coacting form and impression cylinders of a two-color press, and 56, the cross-braces for the sheet-carrier, arranged with annular bars for circumferential division into the 125 five equal sections 57 to 61, inclusive. The form-cylinder 54 is correspondingly divided into four sections, two thereof carrying printing plates R and B, while the remaining two are left blank. The cross-braces 130

of the sheet-carrier are arranged with grippers operated in the manner shown in Figs. 1 and 2, and during the regular operation of the press the sheets are positioned upon the carrier as shown, the arrangement thereof providing for the feed and delivery of a single sheet at each consecutive revolution of the form-cylinder. As indicated, section 57 is provided with a new sheet, section 58 with 10 a sheet having the imprint R, section 59 a sheet with the imprints R and B, sections 60 and 61 are both blank. In the next following revolution of the form-cylinder the carrier will have advanced four divisions, 15 during which time the sheet on section 57 will have received the imprint R, section 58 the R and B imprints, section 59 will deliver its sheet to the tapes 62, section 60 will remain blank, and section 61 will take a new 20 sheet from the feed-table 63 and be advanced to the present position of section 57. It will thus be seen that at each successive revolution of the form and impression cylinders the carrier will receive a new sheet 25 and deliver one upon which two colors have been superimposed, and also, that the relative positions of the remaining sheets upon the carrier with respect to the printing plates and the feed and delivery devices will 30 be common at such successive revolutions.

From the foregoing it will be apparent that an exceedingly simple, compact and accessible construction has been provided for accomplishing work ordinarily requiring a 35 considerably greater number of parts. Also, it will likewise be evident that the sheets as held in undetached relation by the grippers throughout the entire printing operation will afford a perfect register therefor.

40 I am aware that multicolor printing presses have heretofore been designed wherein a rotary sheet carrier operates in conjunction with a plurality of multi-form printing couples to effect superimposed impressions, the carrier operating upon a single sheet at a time and requiring for the completion of the latter a number of revolutions corresponding with the number of 45 separate forms, thus necessitating a periodical tripping action or separation of the printing cylinders between sheet impressions. As thus arranged it will be obvious that not only will the output of the machine be comparatively limited, but if the 50 same is run at considerable speed the tripping action will tend to impair the register of the work. In the present invention it is to be noted that the several forms of the printing couples operate consecutively without interruption upon the several sheets supported at one time upon the carrier, resulting, as above stated, in the delivery of a 55 printed sheet complete at each revolution of the printing couples.

While I have shown and described the 65 preferred embodiment of the invention, it will be obvious that various changes may be made as regards its form, detail construction and general arrangement without departing from the principle and scope of the 70 invention.

What I claim as my invention and desire to secure by Letters Patent, is:

1. In a multicolor printing press, the combination of printing mechanism including 75 a form-cylinder circumferentially divided to form a blank section and a plurality of form sections, severally coacting impression surfaces for said form sections, a sheet-carrier arranged to present a sheet to each one 80 of said forms at successive revolutions of said form-cylinder and including an idle carrier section, and means for delivering said sheet and effecting the registration of the idle carrier section with the blank section 85 of said form-cylinder.

2. In a multicolor printing press, the combination of printing mechanism including 90 a form-cylinder circumferentially divided to form a blank section and a plurality of form sections, severally coacting impression surfaces for said form sections, a multiple-sheet carrier arranged to present alternate sheets to each one of said forms at successive revolutions of said form-cylinder and including an idle carrier section, and means for delivering said sheets and effecting the registration of the idle carrier section with the blank section 95 of said form-cylinder.

3. In a multicolor printing press, the combination of printing mechanism including 100 a plurality of form-cylinders, each thereof circumferentially divided to form a blank section and a plurality of form sections, severally coacting impression surfaces for 105 said form sections, a multiple-sheet carrier arranged to present alternate sheets to each one of said forms at successive revolutions of said form-cylinders and including idle carrier sections, and means for delivering 110 said sheets and effecting the registration of the idle carrier sections with the blank sections of said form-cylinders.

4. In a multicolor printing press, the combination of a form-cylinder circumferentially divided to form a blank section and a plurality of form sections, severally coacting impression surfaces for said form sections, a sheet-carrier provided with a plurality of sheet-carrying sections arranged 115 to present a sheet to each one of said forms at successive revolutions of said form-cylinder and including an idle carrier section, means for feeding a sheet to said carrier at each successive revolution of said form-cylinder, and means for delivering a printed sheet from said carrier at each successive revolution of said form-cylinder and effect- 120 125

ing the registration of the idle carrier section with the blank section of said form-cylinder.

5. In a multicolor printing press, the combination of a plurality of form-cylinders, each thereof circumferentially divided to form a blank section and a plurality of form sections, severally coacting impression surfaces for said form section, a sheet-carrier 10 provided with a plurality of sheet-carrying sections arranged to present a sheet to each one of said forms at successive revolutions of said form-cylinders and including idle carrier sections, means for feeding a sheet 15 to said carrier at each successive revolution of said form-cylinders, and means for delivering a printed sheet from said carrier at each successive revolution of said form-cylinders and effecting the registration of 20 the idle carrier sections with the blank sections of said form-cylinders.

6. In combination with a printing couple provided with a plurality of forms and severally coacting impression surfaces arranged 25 for superimposed impressions, of a sheet-carrier comprising an annular frame including means for carrying a plurality of sheets in a path tangent the printing line of said couple, means for advancing the carrier and 30 presenting the sheets severally to each one of said forms at successive revolutions of said couple and at a speed common with the printing speed, and a series of fixed brushes disposed within said annular carrier frame 35 and having resilient bristles adapted to sup- portably engage the sheets and yield under contact of the carrier frame.

7. The combination of a form-cylinder circumferentially divided to form a blank 40 section and a plurality of form sections, severally coacting impression surfaces for said form sections, a sheet-carrier provided with a plurality of sheet-carrying sections arranged to present a sheet to each one of said 45 forms at successive revolutions of said form-cylinder and including an idle carrier section, means for supplying a blast of air to said sheets for effecting their contact with the impression surfaces and for facilitating 50 the drying action of the impression thereon, and means for delivering said sheet and effecting the registration of the idle carrier section with the blank section of said form-cylinder.

8. The combination of a form-cylinder circumferentially divided to form a blank section and a plurality of form sections, severally coacting impression surfaces for said form sections, independent inking mechanisms for each of said form sections, a sheet-carrier provided with a plurality of sheet-carrying sections arranged to present a sheet to each one of said forms at successive revolutions of said form-cylinder and including 60 an idle carrier section, and means for de-

livering said sheet and effecting the registration of the idle carrier section with the blank section of said form-cylinder.

9. The combination of a form-cylinder circumferentially divided to form a blank 70 section and a plurality of form sections, severally coacting impression surfaces for said form sections, independent inking mechanisms adapted to apply ink of different colors to each of said forms respectively, a sheet-carrier provided with a plurality of sheet-carrying sections arranged to present a sheet to each one of said forms at successive revolutions of said form-cylinder and including an idle carrier section, and means 80 for delivering said sheet and effecting the registration of the idle carrier section with the blank section of said form-cylinder.

10. In combination with a printing couple provided with a plurality of forms and severally coacting impression surfaces arranged for superimposed impressions, of a sheet-carrier comprising a pair of annular side heads mounted for rotation, a series of cross-braces connecting said heads, circumferentially-extending bars fixed to said cross-braces and arranged to support a plurality of sheets movable in a path tangent the printing line of said couple, gripping means 90 coacting with said cross-braces to engage the sheets, and means for advancing the carrier for presenting the sheets severally to each one of said forms at successive revolutions of the printing couple and at a speed common with the printing speed. 100

11. In a multicolor printing press, the combination of rotating printing mechanism comprising a form-cylinder circumferentially divided to form a blank section and a plurality of form sections, an impression-cylinder having impression surfaces coacting severally with said form sections and arranged therewith for consecutive printing action, a sheet-carrier provided with means for carrying a plurality of sheets in a path tangent the printing line of said form and impression cylinders, means for advancing said carrier for presenting the sheets severally to each one of said form sections at successive revolutions of said form-cylinder and at a speed common with the printing speed, means for feeding a sheet to said carrier at each successive revolution of said form-cylinder, and means for delivering a printed sheet from said carrier at each successive revolution of said form-cylinder and effecting the registration of the idle carrier section with the blank section of said form-cylinder. 110 115

12. In a multicolor printing press, the combination of rotating printing mechanism comprising a plurality of form-cylinders each thereof circumferentially divided to form a blank section and a plurality of form sections, a plurality of impression-cylinders 120 125 130

having impression surfaces coacting severally with the form sections of said form-cylinders and arranged therewith for consecutive printing action, a sheet-carrier provided with means for carrying a plurality of sheets in a path tangent the printing line of said form and impression cylinders, means for advancing said carrier for presenting the sheets severally to each one of said form sections at successive revolutions of said form cylinders and at a speed common with the printing speed, means for feeding a sheet to said carrier at each successive revolution.

of said form-cylinders, and means for delivering a printed sheet from said carrier at each successive revolution of said form-cylinders and effecting the registration of the idle carrier section with the blank sections of said form-cylinders.

Signed at New York in the county of ²⁰ New York and State of New York this 21st day of May A. D. 1913.

FREDERICK M. TURCK.
